(57) CLAIM

The ornamental design for an electric toothbrush as shown and described.

DESCRIPTION

FIG. 1 is a perspective view of an electric toothbrush embodying the new design;

FIG. 2 is a right side view, the left side being a mirror image thereof;

FIG. 3 is a front view thereof;

FIG. 4 is a rear view thereof;

FIG. 5 is a top view thereof; and,

FIG. 6 is a bottom view thereof.

In the drawings, the broken lines illustrate portions of the electric toothbrush, and form no part of the claimed design.

1 Claim, 5 Drawing Sheets
